AUDIO-VISUAL INSTRUCTION CARRELL

Albert W. Riswold, 124 Palmetto St., Jesup, Ga. 31545

Filed Mar. 28, 1974, Ser. No. 455,633

Term of patent 14 years

Int. Cl. D6—99

U.S. Cl. D6—25

FIG.1

FIG. 3

FIG. 2

FIG. 4

FIG. 5

FIG. 6

FIG. 7

FIG. 1 is a front elevational view of an audio-visual instruction carrell having five student stations showing the preferred embodiment of my new design;

FIG. 2 is a top view thereof;

FIG. 3 is a side elevational view thereof;

FIG. 4 is a back elevational view thereof;

FIG. 5 is a sectional view thereof taken along line 5—5 of FIG. 1;

FIG. 6 is a bottom view thereof taken along line 6—6 of FIG. 1, the body portion being omitted for clarity;

FIG. 7 is a perspective view of a modified embodiment of my new design providing three student stations;

FIG. 8 is a front elevational view thereof;

FIG. 9 is a top view thereof;

FIG. 10 is a side elevational view thereof; and

FIG. 11 is a sectional view taken along line 11—11 of FIG. 8.

FIGS. 4 and 6 also show the back elevational and sectional views, respectively of the modified embodiment of my new design.

I claim:

The ornamental design for an audio-visual instruction carrell, substantially as shown and described.
